ADJUSTABLE HINGE

Robert G. Polson, Stockton, Calif.

Application October 10, 1950, Serial No. 189,333

2 Claims. (Cl. 16—129)

1

This invention relates in general to improvements in a double-acting spring hinge and check assembly for swing doors.

One object of the invention is to provide novel mounts for the upper and lower vertical pivots or spindles of the hinge assembly; such mounts being arranged to permit the spindles—by easy and convenient manipulation of readily accessible parts—to project said spindles for placement of the door in the door opening in hinged working position, or to retract the spindles to remove the door.

Another object of the invention is to provide a hinge assembly for swing doors, which includes a double-acting, spring actuated closure, and check mechanism of novel construction and function.

A further object of the invention is to provide a hinge assembly, for swing doors, which is simple to install and adjust after installation.

An additional object of the invention is to provide a hinge assembly, for the purpose described, which is designed for ease and economy of manufacture.

Still another object of the invention is to provide a practical and reliable hinge assembly for swing doors, and yet one which will be exceedingly effective for the purpose for which it is designed.

These objects are accomplished by means of such structure and relative arrangement of parts as will fully appear by a perusal of the following specification and claims.

In the drawing:

Fig. 1 is a foreshortened elevation of a door mounted by means of the improved hinge assembly; the upper and lower spindle mounts being in section.

Fig. 2 is a cross section on line 2—2 of Fig. 1.

Fig. 3 is a plan view, partly broken away, of the spring actuated closure mechanism.

Fig. 4 is a sectional elevation of said closure mechanism, as in use.

Referring now more particularly to the characters of reference on the drawing, the improved hinge assembly is adapted for use in connection with a swing door, indicated generally at 1, adapted to be mounted for to and fro swinging movement in a door frame which includes a door jamb 2 upstanding from the floor 3, and a header 4.

The upper and inner corner of the door 1 is pivotally mounted in connection with the header 4 as follows:

A vertical sleeve 5 is disposed in a bore formed

2

in the door 1 from its upper edge, and an upper, vertical spindle 6 is initially slidably disposed in said sleeve 5.

The upper, vertical spindle 6 normally projects a distance above the upper edge of the door 1 and engages in a matching socket 7 of a socket plate 8 secured horizontally to the under side of the header 4.

A rotary shank 9 extends through the door 10 horizontally from its inner edge; such shank at its inner end being formed as a pinion 10 which projects into the vertical sleeve 5 and runs in mesh with a rack 11 formed on the spindle 6 intermediate its ends.

At its outer end the rotary shank 9 includes a slotted head 12 which seats flush in a socket 13 of a plate 14 attached to said inner edge of the door. The shank 9 is rotatable but axially removably secured with respect to the socket 13.

By rotating the head 12 with a screw driver the upper vertical spindle 6 may be caused to move between a retracted and an advanced or projecting position.

When the door 1 is being installed, the spindle 6 is initially in a retracted position, and after the door is disposed in place said spindle is run out or projected, in the manner above described, to engage in the socket 7; all by the simple manipulation of the head 12 with a screw driver.

The above constitutes the upper spindle mount of the hinge assembly; the lower spindle mount comprising the following:

The lower spindle is indicated at 15, and is in substantially vertical alignment with the upper spindle 6; being adjustable, however, in the manner as will hereinafter appear.

The lower spindle 15 is relatively short and projects upwardly in matching relation into a socket member 16; there being a slot and screw arrangement 17 exposed below the door, whereby the lower spindle 15 may be held up within the socket or permitted to drop into a depending position, and as is necessary in connection with the mounting of the door in place, as hereinafter set forth.

The socket member 16 is exteriorly rectangular and engages in a horizontal inverted U-shaped guide channel 18 which is recessed upwardly into the door 1 from its lower edge at the inner corner; such guide channel including, at its outer end, a vertical attachment plate 19 recessed into the rear edge of the door.

The channel 18 and attachment plate 19 are secured in place by screws, as shown.

The socket member 16 includes an ear 20

which upstands through a slot 21 in the top of the inverted guide channel 18, and a horizontal screw rod 22 is threaded through such ear, being rotatably but non-axially movably mounted in connection with said guide channel 18 above the same, as in an eye member 23 threaded into the web of said channel. At its outer end the screw rod 22 is formed with a slotted head 24 which is flush with the attachment plate 19.

Upon rotation of the slotted head 24 by means of a screw driver, with resultant turning of the rod 22, the socket member 16 is caused to move in the guide channel 18, whereby to alter the distance of the spindle 15 from the rear edge of the door. The purpose of this adjustment is of course to attain true vertical alinement of the rear edge of the door relative to the door jamb 2.

The lower spindle 15 engages, when the door is in place and the spindle is lowered as previously described, in detachable connection with a double-acting, spring actuated closure mechanism, indicated generally at 25, and which is constructed in detail as follows:

The closure mechanism 25 comprises a top plate 26 which overlies an opening 27 precut in the floor below the lower inner corner of the door 1; said plate being secured to the floor by screws, as shown, and to the door jamb 2 through the medium of upstanding ears 28 screwed to said jamb.

A case 29 is fixed in connection with the top plate 26 and depends through the floor opening 27, and a vertical axis rotor 30 is disposed in such case; said rotor including a lower trunnion 31 and an upper trunnion 32 journaled in the bottom of the case and in said plate 26, respectively.

The trunnion 32 is formed with an upwardly opening socket 33 into which the lower spindle 15 normally seats; said spindle and socket being of matching non-circular configuration whereby when the door 1 swings one way or the other corresponding part-circle rotation is imparted to the rotor 30. The lower spindle 15 is adjusted downwardly by the slot and screw arrangement 17 so that such spindle seats in the socket 33, as aforesaid.

The rotor 30 is formed with a horizontal cross bore 34 at right angles to the closed position of the door 1, and opposed plungers 35 project into the cross bore 34 from opposite ends; such plungers being socketed at their inner end portions and telescopic, having a heavy-duty compression spring 36 engaged in the socketed portions of said telescoped plungers to urge the latter apart.

At their outer ends the opposed plungers 35 are each formed with a fork 37, which fork straddles a horizontal elliptical track 38 formed in the case 29 about the vertical walls thereof. Rollers 39 are journaled in the forks 37 and ride the inner edge of said elliptical track 38. As the forks 37 straddle the track 38 the rollers 39 are always maintained in proper engagement with said track, without the necessity of any keyway or guide means between the plungers 35 and the rotor 30.

The major axis of the elliptical track 38 is parallel to the normal position of the door 1 so that under the action of the spring 26 the opposed plungers 35 normally seek the position shown in Fig. 3, whereby to maintain the swing door 1 in its closed position. However, upon opening of said swing door 1 90° in either direc-

tion from its closed position, the rollers 39 snap-engage into notches 40 at opposite ends of the elliptical track 38, thereby releasably holding the door in an open position.

With the above described hinge assembly a swing door may be readily initially installed in place or subsequently easily removed; the door when in place being under the effective control of the double-acting spring actuated closure mechanism. While the mounts for the upper and lower spindles 6 and 15, respectively, are of simplified structure, they nevertheless provide for quick adjustment of said spindles between a retracted position which permits the door to be removed, and an advanced or projected position with the door then subject to the control of the mechanism 25.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. In an adjustable hinge adapted to be mounted on a swinging door; said hinge comprising a spindle, a downwardly opening socket member in which the spindle is disposed and from which said spindle projects when the door is mounted in an operative position, a horizontal guide channel in which the socket member is disposed for adjustment along said channel, means securing the guide channel lengthwise to the lower edge portion of the door, and means between the guide channel and socket member operative to so adjust the latter.

2. In an adjustable hinge adapted to be mounted on a swinging door; said hinge comprising a spindle, a downwardly opening socket member in which the spindle is disposed and from which said spindle projects when the door is mounted in an operative position, a horizontal guide channel in which the socket member is disposed for adjustment along said channel, means securing the guide channel lengthwise to the lower edge portion of the door, and means between the guide channel and socket member operative to so adjust the latter; said last named means including a rotary, axially immovable rod mounted in connection with the guide channel and threaded through a part of the socket member, said rod extending to adjacent the rear edge of the door, and a recessed, slotted head on the outer end of the rod.

ROBERT G. POLSON.
